INCLOSED ELECTRIC FUSE.

1,235,555.

Specification of Letters Patent.

Patented Aug. 7, 1917.

Application filed July 28, 1916. Serial No. 111,797.

To all whom it may concern:

Be it known that I, ROBERT C. COLE, a citizen of the United States, residing at Hartford, in the county of Hartford and State of Connecticut, have invented a new and useful Improvement in Inclosed Electric Fuses, of which the following is a specification.

This invention relates to the construction of inclosed fuses of the knife blade terminal type.

The object of the invention is to construct an efficient fuse having a minimum amount of metal, which is composed of parts that can be manufactured very cheaply and assembled in proper condition for the best service very easily, and that can be packed with insulating filler very quickly by any one without liability of injuring the fusible element.

In attaining this end the casing is formed of an insulating tube with short metallic caps closing the ends. Each exterior knife blade terminal and integral interior link terminal is secured to a yoke that is fastened in place by screws which pass transversely through the walls of the tube into the yoke. The caps are secured in place on the ends of the tube by screws that pass longitudinally of the tube through the caps into the yokes, and these screws are utilized to align the exterior terminals, and cause the side screws to be bound and held against accidental displacement as well as to secure the caps in place.

Figure 1 of the accompanying drawings is a side view with one end cut in longitudinal section of a fuse which embodies the invention.

Fig. 2 is a similar view with the fuse rotated on its axis 90°.

Fig. 3 is a view looking at one end of the fuse.

Fig. 4 is a view looking at the end with the cap removed.

Fig. 5 is a side view of one of the conducting terminals and the anchor yoke to which it is connected.

The casing of the fuse is formed of a section of insulating tube 1 of suitable diameter and length. Each exterior terminal or knife blade 2 with its integral interior or link terminal 3 is fastened to the end of a yoke 4, preferably by heading over the studs 5 which extend from one end of the blade through perforations in the end of the yoke.

Each yoke is retained in place in the end of the tube by screws 6 that pass radially through perforations in the sides of the tube into threaded perforations in the limbs of the yoke. Each end cap 7 may be stamped to shape from steel or brass with a short flange of a size to fit the end of the tube and with a slot in the end of a size that fits the knife blade. Each cap is held in place, after it has been slipped over the knife blade and onto the end of the tube, by screws 8 that pass axially of the tube through perforations in the end of the cap into threaded perforations in the end of the yoke. A screen washer 9 is fitted in the bottom of each cap before the cap is placed on the end of the tube and secured to the yoke. This screen is desirably made of canvas or other woven fabric and is designed to permit the escape of air or gas from the interior of the tube through vent perforations 10 in the end of the cap but prevent the powdered or granulated condensing filler 11 from leaking or being blown out from the tube. One or more links 12 of fusible metal having the required capacity have their ends secured to the interior terminals of the knife blades.

In assembling this structure the fusible link connected between the terminals, which have been secured to the yokes, is inserted into the tube. The yokes are then held by turning into them the screws that extend radially through the sides of the tube. After the cap at one end is put over the knife blade and onto the end of the tube and is secured by the screws that extend lengthwise of the tube, the casing is filled with loose insulating material of the desired nature which is employed to condense the gases evolved by the volatilization of the metal when the fuse is blown. After the tube has been filled the other cap is secured in place.

The caps employed with this fuse are very short and each is made of a single stamping. The blades are pivotally held by the side screws that pass into the yokes and are roughly aligned when the caps are placed on the ends of the tube. The blades can be accurately aligned by drawing the yokes from one side or the other by means of the end screws which fasten the caps to the yokes. The screen washers are clamped between the caps and the ends of the tube and the yokes so as to prevent any accidental sifting out of

the filling and they, also, beside acting as vent screens, form cushions which permit the yokes to be drawn by the end screws more or less one way or the other for the purpose of 5 alining the blades. The whole structure is assembled and the parts secured in place except one cap before the filling is put in. As 10 a result of this the filling may be packed in without danger of buckling, or stretching, or breaking, the fusible element. With the 15 short caps permitted by this construction the surface insulation on the fuse is increased. Furthermore, with the short caps there is less metal for the circulation of eddy currents which—particularly, if the caps are 20 stamped from brass and the fuse is used on an alternating current system—tend to cause heating. The end screws passing through the caps draw out the yokes and cause the 25 side screws to bind so as to eliminate the liability of their working out accidentally.

If desired, this fuse can be easily renewed, after being blown, and yet it can be sealed by placing a label 13 as indicated in Fig. 2 25 over the side screws so as to readily indicate if those screws have been removed and the terminals taken out for the insertion of a new fusible element.

I claim as my invention:

30 1. A fuse having a casing formed of an insulating tube and short metal caps at the ends of the tube, knife blade terminals extending through the caps, yokes secured to said terminals within the casing, headed 35 screws passing radially through the sides of

the tube into the yokes near their inner ends in line with the edges of said blades, and headed screws passing axially of the tube through the caps and into the bases of the yokes on each side of said blades. 40

2. A fuse comprising an insulating tube, yokes in the interior at the ends of the tube, headed screws passing radially through the sides of the tube in the yokes near their inner ends, knife blade terminals secured to 45 and extending through the yokes, a fusible element connecting the inner ends of said terminals, granular material filling the tube and surrounding the fusible element, short metallic caps fitting the ends of the tube, 50 and headed screws extending axially of the tube through the caps and into the bases of the yokes on each side of said blade terminals.

3. A fuse comprising an insulating tube, 55 yokes in the interior at the ends of the tube, screws passing radially through the sides of the tube into the yokes, knife-blade terminals secured to and extending through the yokes, a fusible element connecting the inner ends of said terminals, granular material filling the tube and surrounding the fusible element, perforated caps fitting the ends of the tube, venting screens interposed between the inside of the caps and the ends of the 60 tube and the ends of the yokes, and screws extending axially of the tube through the caps and screens into the yokes. 65

ROBERT C. COLE.
